J. ROGERS.

GROUP OF STATUARY.

No. 16,894.

Patented Sept. 7, 1886

M. J. White   *John Rogers.*
W^o Brush

UNITED STATES PATENT OFFICE.

JOHN ROGERS, OF NEW CANAAN, CONNECTICUT.

DESIGN FOR A GROUP OF STATUARY.

SPECIFICATION forming part of Design No. 16,894, dated September 7, 1886.

Application filed August 16, 1886. Serial No. 211,073. Term of patent 14 years.

To all whom it may concern:

Be it known that I, JOHN ROGERS, a citizen of the United States, residing at New Canaan, in the county of Fairfield and State of Connecticut, have invented and produced a new and original Design for a Group of Statuary, of which the following is a specification, reference being had to the accompanying photographs, forming part thereof.

10 The group consists of two standing figures dressed in fancy costume. One of them represents a phrenologist. A cap worn on his head is marked to represent the bumps. He has on a dress-coat and knee-breeches. His left hand is placed on the head of his companion, as if examining his bumps, and his right hand is held beside his mouth, as if he were secretly telling the character he has discovered

to others. The figure whose head is being examined is dressed in Japanese costume. A loose robe reaches to his ankle. A sash is round his waist, and he has loose hanging sleeves. A sword is held by the sash, and he grasps the lower part of it with his left hand. In his right hand he holds a fan, which he raises to screen himself from the phrenologist.

I claim—

The design for a group of statuary herein shown and described, consisting of two standing figures, one dressed to represent a phrenologist, who is examining the head of the other, who is dressed in Japanese costume.

JOHN ROGERS.
